UNITED STATES PATENT OFFICE.

FREDERICK W. CHESSON, OF WATERBURY, CONNECTICUT, ASSIGNOR TO
THE AMERICAN RING COMPANY, OF SAME PLACE.

DESIGN FOR A METAL MOUNT.

SPECIFICATION forming part of Design No. 27,511, dated August 10, 1897.

Application filed December 28, 1896. Serial No. 617,114. Term of patent 7 years.

To all whom it may concern:

Be it known that I, FREDERICK W. CHESSON, a citizen of the United States, residing at Waterbury, in the county of New Haven and State 5 of Connecticut, have invented and produced a new and original Design for Metal Mounts, of which the following is a specification, reference being had to the accompanying drawings, in which—

Figure 1 is an elevation, and Fig. 2 a plan, of my design.

The general configuration of the metal mount is round; and the leading features of my design consist in the convex body portion having semicircular ribs placed circumferentially and extending across in compound or ogee-curved lines, the adjacent bands, and contracted or coved portions.

The convex body portion is shown at *a*, the top and bottom bands at *b b'*, the coved contracted portion at *c*, the cove at *c'*, the bead at *d*, and the large convex body portion at *e*. 20

The convex body portions shown at *a* and *e* are ornamented with semicircular ribs placed circumferentially and extending across in 25 compound or ogee lines.

What I claim is—

The design for a metal mount, substantially as shown and described.

Signed by me this 17th day of December, 30
A. D. 1896.

F. W. CHESSON.
